CLAIM

The ornamental design for a puzzle table as shown and described.

DESCRIPTION

FIG. 1 is a front, top, and left perspective view of a puzzle table showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof;

FIG. 9 is a perspective view of the puzzle table in a raised state;

FIG. 10 is a perspective view of the puzzle table in an extended state;

FIG. 11 is a perspective view of the puzzle table in FIG. 1 with the drawers open; and,

FIG. 12 is a perspective view of the puzzle table in an extended state with the drawers open.

The broken lines shown in the drawings represent portions of the puzzle table that form no part of the claimed design.

1 Claim, 12 Drawing Sheets
